[57] CLAIM

The ornamental design for a microphone, as shown and described.

DESCRIPTION

FIG. 1 is a top front perspective view of a microphone showing my new design;

FIG. 2 is a front elevation thereof;

FIG. 3 is a left side elevation thereof;

FIG. 4 is a rear elevation thereof;

FIG. 5 is a bottom plan view thereof;

FIG. 6 is a top plan view thereof;

FIG. 7 is a top front perspective view of a modified embodiment of the microphone illustrated in FIG. 1;

FIG. 8 is a front elevation of the microphone shown in FIG. 7;

FIG. 9 is a left side elevation of the microphone shown in FIG. 7;

FIG. 10 is a rear elevation of the microphone shown in FIG. 7;

FIG. 11 is a bottom plan view of the microphone shown in FIG. 7;

FIG. 12 is a top plan view of the microphone shown in FIG. 7;

FIG. 13 is a top front perspective view of a further modified embodiment of the microphone illustrated in FIG. 1;

FIG. 14 is a front elevation of the microphone shown in FIG. 13;

FIG. 15 is a left side elevation of the microphone shown in FIG. 13;

FIG. 16 is a rear elevation of the microphone shown in FIG. 13;

FIG. 17 is a bottom plan view of the microphone shown in FIG. 13; and

FIG. 18 is a top plan view of the microphone shown in FIG. 13.
